UNITED STATES PATENT OFFICE

ALBERT E. ROBINSON, OF CINCINNATI, AND WILLIAM L. SCHELLENBACH, OF WYOMING, OHIO, ASSIGNORS TO THE AMERICAN TOOL WORKS COMPANY, OF CINCINNATI, OHIO, A CORPORATION OF OHIO

METAL SHAPING MACHINE

Application filed August 20, 1928. Serial No. 300,873.

Our invention relates to shaping machines for shaping metal, and it is the object of our invention to provide new and useful improvements for supporting and for guiding the work supporting table in a machine of this character.

Work supporting tables in machines of this character are usually heavy structures, and the work supported thereon is also likely to be a heavy structure, the table usually overhanging from the front of the machine, and being adjustable up and down on guideways between the inner end of the table and the frame or column of the machine. The table is also usually adjustable or feedable laterally on the frame or column, on guideways extending laterally between the inner end of the table and the frame or column. The table and the work supported thereon is likely to droop, due to the weight thereof, and in usual structures great strains are exerted upon the laterally extending guideways in adjusting the table laterally, and in feeding the table laterally for feeding movements between the work and the reciprocating tool.

Attempts have been made to support the outer end of the table for supplementing the guideways at the inner end of the table without, however, correcting or minimizing the stresses due to the weight of the table and the work thereon.

It is the object of our invention to provide novel means whereby to support the outer end of the table; further, to provide guiding means for the outer end of the table so arranged as to relieve the strain on the guiding means at the inner end of the table; and, further, to provide supporting means for the outer end of the table so arranged as to slightly raise the outer end of the table for relieving the stresses due to weight upon the inner end of the table, after the adjustments to proximate positions of the table have been made.

It is the object of our invention further to provide novel relief means for relieving the stresses upon the laterally extending guideways for the table.

The invention will be further readily understood from the following description and

claims, and from the drawings, in which latter:

Fig. 1 is a side elevation of so much of a metal shaping machine as is necessary to illustrate our invention, the shaping machine being partly broken away.

Fig. 2 is a front elevation of the same, partly broken away.

Fig. 3 is a front elevation with the front upright removed.

Fig. 4 is a vertical longitudinal section of the same, taken on the line 4-4 of Fig. 2, partly broken away, and the outer guiding means shown in side elevation.

Fig. 5 is a rear elevation of the upper part of the guiding means viewed in the direction of the line 5-5 of Fig. 4, with the table removed.

Fig. 6 is an enlarged vertical section taken on the irregular line 6-6 of Fig. 2, and showing the relieving parts in clamped relations.

Fig. 7 is a similar view, showing the relieving parts in unclamped relation; and,

Fig. 8 is a horizontal section of a detail, taken in the plane of the line 8-8 of Fig. 6.

The frame of the machine is represented at 11. Its column is provided with guideways 12 at its top, in which a tool-ram 13 reciprocates back and forth, the tool-ram having an adjustable tool-slide 14 at its forward end, to which a shaping-tool 15 is secured in usual manner, suitable power means being provided for reciprocating the ram and feeding the tool-slide, which latter may also be manually adjusted. The path of the tool-ram may also be adjusted back and forth in suitable and usual manner.

The front of the frame is provided with vertical guides 21 on which a cross-rail 22 is adjustable up and down, the cross-rail being provided with vertical guideways 23 complementary to the guides 21. Suitable means are provided for adjusting the cross-rail up and down, either manually or by power, as may be desired, illustrated as comprising a vertical screw 24 fixed in a step-bearing 25 on the base 26 of the frame. The screw is threaded in a rotatable nut 27, journaled in the cross-rail and having a bevel-gear 28 rigid therewith. A bevel-gear 29 meshes with the

bevel-gear 28, and is fixed to an adjusting shaft 30, journaled in bearings in the cross-rail, and provided with rotating means, shown as a squared end 32, arranged for receiving a suitable adjusting wrench.

A work supporting table is arranged to be moved laterally on the frame. Thus the cross-rail is exemplified as provided with an upper guide 35 and lower guide 36. A saddle 37 is provided with a complementary upper guide 38 and a complementary lower guide 39. The upper guides are represented as angular and as having upper, rear and front guide faces, part of the rear guide faces being on an adjustable gib 40. The lower guides are exemplified of dove-tail form, the guide 39 being on an adjustable gib. Upper and lower upright guides 41, 42, respectively are exemplified on the front face of the cross-rail 20 and the rear end of the saddle.

The table is exemplified as a universal table. The saddle is shown provided with a forwardly extending trunnion 45 about which there is a table 46, having a suitable number 25 of work-securing surfaces. The table is provided with bearings 47, 48, about the trunnion, and with an end bearing face 49 complementary to the end bearing face 50 on the saddle. The trunnion is provided with an 30 annular rack 51, with which a worm 52 meshes. The worm is fixed to an adjusting shaft 53, journaled in bearings in the table, and provided with means for rotating the same, exemplified as a squared end 54 arranged to receive a suitable wrench.

The front end of the trunnion is provided with an apron 55, having an annular end bearing face 56, against the annular end bearing face 57 of the table. Clamp studs 58 are received through holes in the apron and in threaded holes in the end of the trunnion. Nuts 59 received about the outer threaded ends of the studs are arranged to clamp the table between the end bearing face 50 on the 45 saddle and said apron.

A supplemental work supporting table 60 is adjustable on the table 46 in suitable manner.

The work supporting table is arranged to support the work, represented at 61, suitably 50 fixed to the supplemental table or to the main table. The table or work support is a universal table, although the same may be a simple table of usual form or of other suitable structure without departing from the 55 spirit of my invention as stated in the accompanying claims.

In the usual operation of a machine of this character, the table is caused to be moved laterally with relation to the frame, this lateral movement being represented as taking place on the cross-rail. This lateral movement of the table may be an adjusting movement, for placing the table in a laterally adjusted position, or feeding movements for 60 successively placing new parts of the work 65

in coactive relation with the reciprocating tool.

The means exemplified for this purpose comprise a feed-screw 65 journaled in bearings 66 in the cross-rail and threaded in a 70 nut 67 fixed to the saddle. The feed-screw may be manually rotated in suitable manner, as by means of a suitable wrench received over the square end 68 of the feed-screw, or may have intermittent feeding movements 75 imparted thereto in either direction by any usual power feeding means, indicated generally by the numeral 69. The feeding mechanism may be such for instance as shown and described in United States Letters Patent 80 No. 1,637,969, granted August 2, 1927, on the application of A. M. Sosa, for feeding mechanism for metal working machinery.

During such lateral movements of the table, in the present exemplification, the 85 guides at the rear of the saddle move laterally along the guides on the front of the cross-rail. The table overhangs the cross-rail or forward end of the frame, so that great binding stresses are exerted upon these 90 guides, making it difficult to obtain such lateral movements, and causing great stresses upon the parts, and the expenditure of great power in effecting such movements, especially in heavy types of machines. Means for 95 relieving such strains or counteracting or minimizing the same will now be described.

The forward end of the table is provided with a guideway 71. This guideway is represented in a lower extension 72 of the apron 100 55. One of the walls of this guideway is shown as a gib 73 secured to the lower end of the apron by means of bolts 74.

An outer support for the table is shown as an upright support 75. It is shown as an 105 outer upwardly extending flange. A foot-piece 76 thereof is bolted to the front end of the base by bolts 77. The lower end of the upright support is held to the foot-piece, as by means of bolts 78 received through holes 110 in the lower end of the upright support and threaded into the foot-piece for rigidly fixing the upright support to the base. Locating pins 79 are between these parts.

A guide 84 for supporting the front end of the table is adjustably secured to the upright support, and means are provided for complementally adjusting the guide for relieving the strains between the table and the cross-rail or frame of the machine.

In the exemplification shown for accomplishing this purpose there is a guide-bar 85. The guide-bar is provided with a groove 86, which has a lower wall 87 and an upper wall 88. These walls slant upwardly and outwardly and are complementary to similarly slanting lower and upper walls 89, 90, on the guide 84, which has lower and upper guide-faces 91, 92, complementary to the lower and upper guide-faces 93, 94, of the guideway 71 130

in the apron. For convenience the upper slanting face 88 is on a gib 95 secured to the body of the guide-bar 85 by means of screws 96 received through holes in the gib and threaded into the guide-bar.

5 Studs 101 are fixed in the guide-bar and are adjustable up and down in slots 102 of the upright support, nuts 103 being threaded over the outer end of the studs, for clamping the guide-bar in adjusted positions up and down on the upright support, according to the vertical adjustments of the table. Studs 105 are fixed in the guide and are received through holes 106 in the guide-bar and 10 through the slots 102, nuts 107 being threaded over the outer end of these studs for clamping the guide, the guide-bar, and the upright support together. Clamp-plates 108 are received between the upright support at 15 the slots therein and the nuts 103, 107.

20 Springs 111 are received in recesses 112 in the guide for normally separating the complementary walls 113, 114, on the guide and the guide-bar respectively in the bottom of 25 the groove 86 in the guide-bar. These springs normally separate these walls and cause the slanting faces on the guide to move slantingly downward on the slanting faces on the guide-bar. (See Fig. 7). These complementary faces are normally in contact with 30 each other when the parts are in clamped relation for fixing the distance of rise of the outer end of the table. (See Fig. 6).

35 This separated relation between the guide and the guide-bar is the normal relation between these parts during vertical adjustment of the table. When this vertical adjustment has been effected, the guide-bar is clamped in 40 adjusted position to the upright support by screwing up the nuts 103, for fixing the elevation of the slanting faces 87, 88, on the guide-bar.

45 The nuts 107 are thereupon tightened, thereby drawing the guide toward the guide-bar, and causing the inclined walls on the guide to climb upwardly on the inclined walls of the guide-bar for raising the guide, and thereby correspondingly raising the outer or overhanging end of the table. This results 50 in relief upon the guide faces between the table and the frame of the machine, or specifically the guide-faces between the saddle and the cross-rail, and relieves the pressure between said guide faces due to the weight of 55 the table, including the saddle, and the work upon the same.

60 This elevating movement of the outer end of the table is in practice very slight, and may be exemplified as an elevation for example of only a few thousandths of an inch, but it is sufficient to relieve the binding stresses between the laterally extending guideways which support the table at the inner end of 65 the same, and counteract a drooping tendency of the table and the work thereon, and insures

accuracy in the work performed by the machine, and ease of operation of the parts. The amount of such relief is in practice usually definite.

70 The stud 105 is provided with a shoulder 117 received in an enlargement 118 at the outer end of each of the holes 106. This shoulder has slight axial movement in said enlargement between the bottom of said enlargement and the upright support 75, and limits the 75 separating movements between the guide and the guide-bar. There is preferably an upright space 119 between the bottom of the guide groove 71 and the inner end of the guide, to permit movement of the guide toward and from said bottom during the relative movements between the guide and the guide-bar.

80 In operation, assuming that work has been 85 performed on the machine, and that it is desired to change the elevation of the table, the nuts 103, 107, are released. Releasing the nuts 107 permits the guide to recede from the guide-bar and permits lowering of the guide with relation to the guide-bar, the receding of the guide from the guide-bar being aided by the springs 111. The release of the nuts 103, 107, releases the clamped relation between the guide, the guide-bar and the upright support 75.

90 The table may now be adjusted vertically by rotation of the adjusting shaft 24. During such adjustment, the guide and the guide-bar will move to corresponding elevation with the table on the upright support, the studs 101, 105, moving vertically in the slots 102. When the table has been adjusted to the desired elevation, during which the weight of the table and the work thereon exerts full pressure upon the laterally extending guideways between the table and the frame, the nuts 103 are drawn tight to securely clamp the guide-bar in its assumed adjusted position to the upright support.

100 After the guide-bar has been securely clamped to the upright support, the nuts 107 are drawn taut, whereby the guide is moved in its guide slot in the guide-bar and the outer end of the table is elevated by reason of the 105 inclined form of the guide faces 89, 90, on the guide and the slanting supplemental faces 87, 88, on the guide-bar, whereby the guide is slightly raised, and the guide and the guide-bar and the upright support are firmly 120 clamped together.

110 This results in slight elevation of the outer end of the table and a slight upward tilting of the table toward the frame so as to relieve 125 the undue pressure, due to the weight of the table and the work, from the laterally extending guide faces between the table and the frame, and levels the outer end of the table with the inner end of the same, and counteracts the pressure of the tool upon the 130

work, and permits more accurate work to be performed.

The extent of this correcting elevation of the outer end of the table by this supplemental elevating means is definite, due to the climbing of the upwardly outwardly inclined faces 89, 90, on the complementary faces 87, 88, to the extent of the movement of the shoulder 117 from the bottom wall to the outer end of the recess 118, or to the contact relation of the complementary walls 113, 114, exemplified by a comparison of Figs. 7 and 6.

The coaction between the inclined faces causes a raising of the guide 84, thereby raising the guideway 71 and the outer end of the table a definite amount, after the guide-bar 85 has been clamped in place on the upright support 75, upon completion of the adjustment to elevation of the table by means of the screw 24.

This supplemental elevating of the outer end of the table is from a normal sagging condition of the outer end of the table, which is the same throughout all adjustments to elevation of the table.

This definite supplemental elevating of the outer end of the table from its normal sagging relation after clamping of the guide-bar, relieves the binding pressure there would otherwise be on the guides 35, 36, 41, 42, in the transverse feeding movements of the saddle, and avoids danger of insufficient relief, and also of undue amount of upward tilting of the outer end of the table which would result in binding stresses in opposite direction on the guides 35, 36, 41.

The operation of the machine may thereupon proceed with great relief of manual or power adjusting or feeding stresses between the table and its laterally extending guides.

By means of our improved device the laterally extending guiding means for the table are relieved of binding stresses, greater accuracy in work is obtained, and a great saving in power is accomplished, and wear on the parts is greatly reduced.

Having thus fully described our invention, what we claim as new, and desire to secure by Letters Patent, is:

1. In a metal shaping machine, the combination of a frame, a table overhanging from said frame, upright guiding means and adjusting means between the inner end of said table and said frame for adjusting said table to elevation, laterally extending guiding means and adjusting means between the inner end of said table and said frame for laterally translating said table, an upright support for the outer end of said table, a connected laterally extending guide-bar and guide movable elevationally on said upright support and said guide having laterally extending supporting guide and slide connection with said outer end of said table, so that said

guide-bar and guide move up and down on said upright support with the elevational adjustments of said table, and means clamping said guide-bar to said upright support upon completion of said elevational adjustments, said guide and guide-bar provided with supplemental elevating means elevating said guide on said guide-bar and thereby elevating said laterally extending slide connection between said guide and the outer end 75 of said table.

2. In mechanism of the character described, the combination of a frame, a cross-rail, means for adjusting said cross-rail to height on said frame, a saddle, means for guiding and feeding said saddle laterally on said cross-rail, said saddle comprising a trunnion overhanging from said saddle, a table adjustable about said trunnion, an apron at the outer end of said table, means securing said apron to said trunnion, said apron provided with a laterally extending guide, an outboard upright support at the outer end of said table, a second laterally extending guide and a support therefor on said outboard upright support having continuous operative connection with said first-named guide for adjustments thereof up and down on said outboard upright support with the up and down adjustments of said cross-rail, securing means securing said second-named support in said adjusted positions to said outboard upright support, said second-named support and said second-named laterally extending guide having inclined faces between them inclined in directions intersecting the axis of said trunnion to cause upward movement of said second-named laterally extending guide by shifting movement between said inclined faces, and means to cause said shifting movement.

3. In a machine of the character described, the combination of a frame, a base, a table overhanging said base from said frame, adjusting means for adjusting said table to elevation on said frame, means including laterally extending guides for laterally feeding said table on said frame, the outer end of said table having a natural droop with relation to the inner end of said table on said laterally extending guides, an upright support on said base at the outer end of said table, an anchoring part thereon having laterally extending slide connection with the outer end of said table and connection in up and down direction with said outer end for adjustment of said anchoring part to elevation with said table, releasable securing means between said anchoring part and said upright support arranged for securing said anchoring part to said upright support upon each completed adjustment to elevation of said table, and supplemental raising means between said anchoring part and said outer end of said table effective after such secured relation of 130

5 said anchoring part to said upright support, said supplemental raising means comprising coacting faces, and means for causing shifting movement between said coacting faces, the directions of said coacting faces being such as to cause change in elevation between said outer end of said table and said anchoring part upon such shifting movement between said coacting faces for counteracting such natural droop of said outer end of said table.

10 4. In a machine of the character described, the combination of a frame, a base, a table overhanging said base from said frame, adjusting means for adjusting said table to elevation on said frame, means including laterally extending guides for laterally feeding said table on said frame, the outer end of said table having a natural droop with relation to the inner end of said table on said 15 laterally extending guides, an upright support on said base at the outer end of said table, an anchoring part thereon having laterally extending slide connection with the outer end of said table and connection in up and down 20 direction with said outer end for adjustment of said anchoring part to elevation with said table, releasable securing means between said anchoring part and said upright support arranged for securing said anchoring part to 25 said upright support upon each completed adjustment to elevation of said table, and supplemental raising means between said anchoring part and said outer end of said table effective after such secured relation of said anchoring 30 part to said upright support, said supplemental raising means comprising coacting faces and means for causing shifting movement between said coacting faces, the directions of said coacting faces being such as to cause change in elevation between said outer 35 end of said table and said anchoring part upon such shifting movement between said coacting faces, and a stop for limiting such movement between said coacting faces.

40 5. In a shaping machine, the combination of a frame, a table overhanging said frame, adjusting means for adjusting said table to elevation on said frame, means including laterally extending guides for laterally feeding said table on said frame, an upright outboard support for the outer end of said table, a laterally extending guide having supporting guide connection with the outer end of said table, a guide-bar, said guide and said 45 guide-bar having coacting inclined faces connecting said guide and said guide-bar in upright direction, arranged for elevational movement of said guide and said guide-bar with said table, releasable securing means between said guide-bar and said upright outboard support for fixing said guide-bar to said upright outboard support upon completed adjustment to elevation of said table, and means between said guide-bar and said 50 guide relatively shifting the same along said

inclined faces for imparting supplemental elevation to the outer end of said table.

6. In a shaping machine, the combination of a frame, a table overhanging said frame, adjusting means for adjusting said table to elevation on said frame, means including laterally extending guides for laterally feeding said table on said frame, an upright outboard support at the outer end of said table, a laterally extending supporting guide between the outer end of said table and said upright outboard support, a guide-bar interposed between said guide and said upright outboard support, said guide and said guide-bar having coacting supporting inclined wedge faces between them, said connections between said outer end of said table, said guide and said guide-bar causing combined elevational movements of said outer end of said table, said guide and said guide-bar, means for clamping said guide-bar to said upright outboard support in such elevational positions, and clamping means between said guide and said guide-bar causing wedging movement between said wedge faces for supplemental elevation of said guide with relation to said guide-bar causing supplemental raising of the outer end of said table, and resilient means between said guide and said guide-bar causing unwedging movement between said wedge faces.

7. In a shaping machine, the combination of a frame, a table overhanging said frame, adjusting means for adjusting said table to elevation on said frame, means including laterally extending guides for laterally feeding said table on said frame, an upright outboard support on the outer end of said table, a laterally extending supporting guide between the outer end of said table and said upright outboard support, a guide-bar interposed between said guide and said upright outboard support, said guide and said guide-bar having coacting supporting inclined wedge faces between them, said connections between said outer end of said table, said guide and said guide-bar causing combined elevational movements of said outer end of said table, said guide and said guide-bar, means for clamping said guide-bar to said upright outboard support in such elevational positions, clamping means between said guide and said guide-bar causing wedging movement between said wedge faces for supplemental elevation of said guide with relation to said guide-bar causing supplemental raising of the outer end of said table, resilient means between said guide and said guide-bar causing unwedging movement between said wedge faces, and limiting means for the latter.

8. In mechanism of the character described, the combination of a frame, a table overhanging from said frame, upright guiding means and adjusting means between the inner end of

said table and said frame, laterally extending guiding means between said frame and the inner end of said table, the outer end of said table provided with a laterally extending 5 guide part, a laterally extending guide coacting therewith, a guide-bar, said guide and said guide-bar having wedge faces between them, the connections between said guide part, guide and guide-bar being such as to cause elevational movement of said guide-bar with said table, an upright outboard support for the outer end of said table, clamping means between said guide-bar and said upright outboard support for clamping said 10 guide-bar in elevational positions to said upright outboard support, and clamping means between said guide, said guide-bar and said upright outboard support, clamping said guide and said guide-bar to said upright outboard support and causing wedging movement between said wedge faces for supplemental elevation of said outer end of said table.

9. In mechanism of the character described, the combination of a frame, a table overhanging from said frame, upright guiding means and adjusting means between the inner end of said table and said frame, laterally extending guiding means between said 25 frame and the inner end of said table, the outer end of said table provided with a laterally extending guide part, a laterally extending guide coacting therewith, a guide-bar, said guide and said guide-bar having wedge faces 30 between them, the connections between said guide part, guide and guide-bar being such as to cause elevational movement of said guide-bar with said table, an upright outboard support for the outer end of said table, clamping means between said guide-bar and said 35 upright outboard support for clamping said guide-bar in elevational positions to said upright outboard support, clamping means between said guide, said guide-bar and said upright outboard support, clamping said guide and said guide-bar to said upright outboard support and causing wedging movement between said wedge faces for supplemental elevation of said outer end of said 40 table, and means limiting unwedging movement between said guide and said guide-bar.

10. In mechanism of the character described, the combination of a frame, a table overhanging from said frame, upright guiding means and adjusting means between the inner end of said table and said frame, laterally extending guiding means between said 45 frame and the inner end of said table, the outer end of said table provided with a laterally extending guide part, a laterally extending guide coacting therewith, a guide-bar, said guide and said guide-bar having wedge faces between them, the connections between said guide part, guide and guide-bar being such as to cause elevational movement of said 50

guide-bar with said table, an upright outboard support for the outer end of said table, clamping means between said guide-bar and said upright outboard support for clamping said guide-bar in elevational positions to said upright outboard support, and clamping means between said guide, said guide-bar and said upright outboard support, clamping said guide and said guide-bar to said upright outboard support and causing wedging movement between said wedge faces for supplemental elevation of said outer end of said table, and resilient means between said guide and said guide-bar causing separating movement between said guide and said guide-bar. 55

In testimony whereof, we have hereunto signed our names.

ALBERT E. ROBINSON.
